UNITED STATES PATENT OFFICE.

BENJAMIN RICHARD CROMWELL, OF DAYTON, OHIO.

BODY-TREATING APPARATUS.

Application filed September 21, 1923. Serial No. 664,000.

To all whom it may concern:

Be it known that I, BENJAMIN RICHARD CROMWELL, a citizen of the United States, residing at Dayton, in the county of Montgomery and State of Ohio, have invented certain new and useful Improvements in Body-Treating Apparatus, of which the following is a specification.

This invention relates to body treating apparatus and more particularly to means whereby the different parts of the body may be subjected to a heat treatment for sweating out through the pores thereof, the germs of different diseases for thereby providing I believe, an absolute cure for certain otherwise almost incurable diseases.

The main purpose of my invention is to provide such a body treating apparatus wherein the same comprises a steam generating plant that includes therein supporting elements for certain chemicals the effluvia of which are drawn off by the steam and led to certain devices for the reception of the head, feet and legs and body of the patient, whereby the same will be subjected to the chemically treated vapors for drawing out of the body, through the pores thereof, disease germs.

A further object of this invention is to provide such a body treating apparatus that is extremely simple of construction and one that may be manufactured and marketed at small cost so as to enable the procuring of the same by the public in general.

With the above and other objects in view which will appear as the nature of the invention is better understood, the same comprises the novel form, combination and arrangement of parts hereinafter more fully described, shown in the accompanying drawings and claimed.

In the drawings wherein like reference characters indicate corresponding parts throughout the several views,

Figure 1 is a front elevational view of the vapor generating means that includes an essential part of my present body treating apparatus,

Figure 2 is a front elevational view of the body treating cabinet, the side wall thereof being broken away for disclosing the interior thereof,

Figure 3 is a detail sectional view through the vapor generating means shown in Figure 1,

Figure 4 is a transverse cross section

thereof and taken substantially upon the line 4—4 of Figure 1,

Figure 5 is a side elevational view of the head treating cabinet of this invention, 60

Figure 6 is a detail section thereof,

Figure 7 is a side elevational view of the feet and leg treating means, and

Figure 8 is an end view thereof.

First having reference to Figures 1, 3 65 and 4, wherein there is shown a novel vapor generating means that includes a support interiorally thereof for receiving certain chemicals that co-mingle with the vapors and are carried off thereby for purposes 70 presently to be set forth, 5 indicates a casing preferably circular in cross section and opened at its lower end. Supported within this casing by brackets 6 adjacent the lower open end thereof is a water tank 7 formed centrally with a vertical open-ended conical-shaped heat radiating tube 8 beneath which tube is a suitable form of gas or fluid fuel burner 9 for thoroughly heating this tube 8 and consequently heating the water 80 within the receptacle 7 for producing steam. The casing 5 adjacent its lower end is formed 75 with a circular row of openings 10 for the entrance of air, and being also provided at this lower end with a door 11, Figure 1, 85 whereby the burner may be removed for cleaning and repair purposes.

Extending through the casing 5 and leading into the receptacle 7 is a water pipe 12 that is in communication at its outer end 90 with a water level gauge 13, this pipe 12 also having communication with a valved pipe 14 that is in communication at its opposite end with a water tank 15 into which extends a supply pipe 16 the flow of water there-through being controlled by a float operated valve 17, Figure 1, it being obvious that when the supply of water within the receptacle 7 is low the valve within the pipe 14 95 may be opened for supplying the same from the tank 15.

The casing 5 may be preferably formed in an upper and lower section, Figure 1, which sections are rigidly joined together by an internal ring that is welded or otherwise 105 suitably secured to the interior of the casing sections upon which is supported a pan-shaped tray 18. The bottom wall of this pan-shaped tray is formed with a central opening surrounding which is a relatively 110 wide flange 19 co-extensive with the upper end of the before mentioned heat radiating

tube 8 of the receptacle 7 whereby the heat from the burner 9 as well as the steam generated strikes a circular disk 20 supported above the bottom wall of said pan-shaped tray and that carries upon its top surface pedestals 21 for receiving kegs of certain desired chemicals whereby the properties thereof will co-mingle with the steam and heated air passing upwardly through the casing to be carried off to the different treating cabinets for assisting in the curing of certain diseases.

The upper section of the casing 5 is equipped with an entrance shaft 22 whereby the kegs of chemicals may be positioned and whereby the tray, etc., may be removed for cleaning or repair purposes.

The upper end of the casing 5 is equipped with a discharge pipe 23 that is in turn equipped with a damper 24, this pipe 23 being in communication with a horizontal drum 25 from which extends a vapor conveying pipe 26 that leads to a drum 27 in which are caught the condensed vapors for preventing passage of the same to the different body treating devices through the medium of a pipe 28. Leading into the before mentioned drum 25 at its opposite end is an air inlet pipe 29 that is equipped with a damper 30 for obvious purposes.

In Figures 5 and 6 wherein there is shown the head treating cabinet, 31 designates a drum-shaped casing that is formed at its front side with an opening to one edge of which is hingedly connected a door 32. The bottom wall of this casing is provided with a relatively wide slot 33 registering at its front end with the before mentioned opening in the front side of said casing for receiving the neck of the patient. The door 32 is formed with a suitably shaped opening 34 through which projects the face of the patient when the door is closed, for preventing suffocation, the edges of the opening in said door being covered with a suitable material 35 for preventing the cutting of the face, this covering being provided on its outer side with hooks 36 whereby a towel may be secured thereto for allowing the patient to mop his face as the head is being subjected to the vapor treatment, this casing 31 receiving its vapor and heated air supply from a flexible tube 36 that leads into said casing at the upper end thereof and is attached at its opposite end to the before mentioned pipe 28 of the steam generating apparatus.

Upon opposite sides of this casing 31 are relatively long links 37 that are pivoted at their upper ends as at 38 to the casing and have pivotally secured thereto the forward ends of spaced parallel rearwardly extending flat-like rods 39 that are pivotally secured at their inner ends to brackets 40 rigidly secured to the wall or other suitable sup-

port. These flat-like rods 39 are normally separated for maintaining the casing in the position shown in Figures 5 and 6, by springs 41 that are connected at their opposite ends to the parallel bars upon opposite sides of said casing 31, it being obvious that when the patient is seated upon a chair or other support 42 and the door 32 of the casing opened this casing may be swung downwardly for allowing of the proper position of the head therein.

In Figure 2 there is shown a cabinet for the vapor treatment of the entire body with the exception of the head that includes a relatively large casing 43 preferably circular in cross section and formed with a conical top 44 in the apex of which is a circular opening through which the head of the patient extends. Interiorly of this casing 43 and supported above the lower edge thereof is a floor 45 that is dished as shown, whereby the condensed vapors will be conveyed to an outlet pipe 46, the chemically treated steam and hot air entering this cabinet through a pipe 47 that has communication with the before mentioned pipe 28 of the generating apparatus.

The casing 43 and its conical top 44 are provided with registering inlet doors 43' and 44' respectively, for allowing the patient to enter the cabinet.

In Figures 7 and 8 there is shown a means whereby the feet and legs of the patient may be subjected to my vapor process, this means comprising essentially a base 48 the top wall thereof being inclined rearwardly as shown and being formed with a pair of spaced parallel extending circular channels 49 within which are positioned adjustable cylinders 50 each of which comprises an outer and an inner shell, 51 and 52, respectively. As more clearly shown in Figure 7 the outer shell 51 is closed at its lower end and is adapted for slidably receiving the shell 52 which is open at its opposite end and may be slid outwardly of the shell 52 for accommodating the cylinders to different lengths of legs.

Each of the before mentioned cylinders 50 has communication with a drum 53 through the medium of a valved pipe 54 it being of course understood that said drum 53 is in communication through the medium of a flexible or other pipe, not shown, with the before mentioned pipe 28 of the vapor generating apparatus. For carrying off the condensed vapors each cylinder is provided with an outlet nipple 55.

The specific operation together with numerous advantages of a body treating apparatus of this character will be at once appreciated by those skilled in the medical art and even though I have herein set forth the most practical embodiments of this invention with which I am at the present time

familiar, it is nevertheless to be understood that minor changes may be made therein without departing from the spirit and scope of the appended claims.

5 Having thus described my invention, what I claim as new and desire to secure by Letters Patent is:—

1. In a body treating apparatus, means for generating chemically treated vapors including a casing, a water receptacle within the casing, means for heating the water within the receptacle, a support within the casing and above said water receptacle for receiving medicinal chemicals the effluvia 15 of which are to be extracted by the generated steam during the travel of the same upwardly, and a cabinet in communication with said vapor generating means for receiving the part of the body to be treated.
- 20 2. In a body treating apparatus, means for generating chemically heated vapors, said means comprising a vertically elongated casing, a water receptacle within the

lower part of said casing, the bottom of said receptacle being fashioned to form a 25 heat radiant, heating means for producing a flame to impinge upon said radiant, a partition within said casing and above said water receptacle, said partition being formed with a centrally located opening, 30 through which steam laden vapors pass, a deflector supported in spaced relation above said partition and over said opening in the latter, said partition being adapted to support medicinal preparations, the curative 35 properties of which are extracted by the surrounding and upwardly passing steam, and a discharge conduit for the chemically treated vapors.

3. A structure as set forth in claim 2, 40 wherein said discharge conduit is provided with a passage, for admitting atmospheric air, said conduit being also formed with a condensation trap.

In testimony whereof I affix my signature.

BENJAMIN RICHARD CROMWELL.
